(57) **CLAIM**

The ornamental design for a scissor, as shown and described.

DESCRIPTION

FIG. 1 is a perspective view of an embodiment of a scissor showing my new design;

FIG. 2 is a left side view thereof;

FIG. 3 is a right side view thereof;

FIG. 4 is a bottom view thereof;

FIG. 5 is a top view thereof;

FIG. 6 is a front view thereof;

FIG. 7 is a rear view thereof;

FIG. 8 is a perspective view of a second embodiment of a scissor showing my new design;

FIG. 9 is a left side view thereof;

FIG. 10 is a right side view thereof;

FIG. 11 is a bottom view thereof;

FIG. 12 is a top view thereof;

FIG. 13 is a front view thereof; and,

FIG. 14 is a rear view thereof.

The broken line portions shown in FIGS. 8 to 14 are for illustrative purposes only and form no part of the claimed design.

The scissor may be arranged as an eyebrow scissor, e.g., its blade may be particularly sized to be able to get close to the eyebrow hair.
